UNITED STATES PATENT OFFICE.

KARL STEPHAN, OF BERLIN, GERMANY, ASSIGNOR TO CHEMISCHE FABRIK
AUF ACTIEN VORM. E. SCHERING, OF BERLIN, GERMANY.

PROCESS OF MAKING CAMPHENE.

SPECIFICATION forming part of Letters Patent No. 725,890, dated April 21, 1903.

Application filed June 4, 1902. Serial No. 110,226. (No specimens.)

To all whom it may concern:

Be it known that I, KARL STEPHAN, chemist, doctor of philosophy, a subject of the Emperor of Germany, residing at Berlin, Kingdom of Prussia, German Empire, have invented a new and useful Improvement in Processes of Manufacturing Camphene free from Chlorin, of which the following is a specification.

10 The invention relates to the manufacture of camphene free from chlorin by reacting with bases upon pinene hydrochlorid (bornyl-chlorid) in watery solution and using the alkaline salts of the higher fatty acids, especially all kinds of soap, as a solvent. In the presence of such substances the action of the bases upon pinene hydrochlorid is performed in a perfect manner even in watery solution.

15 The manufacture of camphene by heating pinene hydrochlorid with dry powdered soap is known, (*Berthelot, Annalen der Chemie* 110, page 367, and *Comptes Rendus* 47, page 266.) In this reaction the alkali is withdrawn from the alkaline salt of a fatty acid with the

20 formation of free fatty acid, the alkali being utilized for splitting the hydrochloric acid off from the pinene hydrochlorid. Under the conditions given (heating to from 240° to 250° Celsius for forty hours) the reaction only succeeds when a very large excess of powdered soap is used, according to Berthelot eight times the theoretical amount. If, however, according to my invention an alkaline salt of the higher fatty acids, especially all kinds

25 of soaps, be used not as a reagent, but as a solvent for pinene hydrochlorid, and the hydrochloric acid be split off by means of bases, the reaction proceeds quite smoothly, and camphene free from chlorin is obtained in 30 good yield without using an excess of soap. It is even sufficient to use half a molecule of soap referred to as "pinene hydrochlorid."

35 Example 1: Ten kilograms of pinene hydrochlorid are heated in an autoclave for twenty hours to from 210° to 220° Celsius, together with ten kilograms of soap—for instance, sodium or potash soap, or a mixture of both—four kilograms of sodium hydrate,

and five kilograms of water. After cooling the product of reaction is acidified and the 50 camphene produced driven over with steam.

Example 2: Ten kilograms of pinene hydrochlorid are heated for twenty hours to 210° Celsius, together with 5.3 kilograms ammonia-soap (ammonia stearate) and five kilograms of watery ammonia, whereupon the product of reaction is purified in the same manner as indicated in the foregoing example.

It is still more preferable not to use the 60 ready-made ammonia-soap, but to combine an excess of watery ammonia with stearic acid—for example, six kilograms of watery ammonia (specific weight 0.910)—and five kilograms of stearic acid, whereby ammonia 65 stearate is formed and an excess of ammonia remains for the action upon the pinene hydrochlorid.

By using other bases the production of camphene takes place in an analogous manner. 70 In all cases the camphene is obtained free from chlorin.

I claim as my invention—

1. The process of manufacturing camphene free from chlorin which consists in heating a 75 hydrogen-haloid compound of pinene with a base in watery solution in the presence of an alkali salt of the higher fatty acids as a solvent for said pinene compound, and isolating the camphene so formed, substantially as set forth.

2. The process of manufacturing camphene free from chlorin which consists in heating pinene hydrochlorid with a base in watery solution in the presence of soap as a solvent 85 for said pinene hydrochlorid, and isolating the camphene so formed, substantially as set forth.

In testimony whereof I have signed my name to this specification in the presence of 90 two subscribing witnesses.

KARL STEPHAN.

Witnesses:

HENRY HASPER,
WOLDEMAR HAUPT.
